The ornamental design for a eyeglass retainer, as shown.

DESCRIPTION

FIG. 1 is a perspective view.

FIG. 2 is a top view of the eyeglass retainer in an alternate position, the bottom view being a mirror image thereof;

FIG. 3 is a right side view thereof, the left side view being a mirror image thereof;

FIG. 4 is a front view thereof; and,
FIG. 5 is a rear view thereof.

The broken line showing of the eyeglasses in FIG. 1 is for illustrative purposes only and forms no part of the claimed design.
